UNITED STATES PATENT OFFICE

154,009

DESIGN FOR A BOOK END

Julius H. Witzke, Chicago, Ill.

Application January 31, 1947, Serial No. 136,581

Term of patent 14 years

(Cl. D33—1)

To all whom it may concern:

Be it known that I, Julius H. Witzke, a citizen of the United States, residing at Chicago, in the county of Cook and State of Illinois, have invented a new, original, and ornamental Design for a Book End, of which the following is a specification, reference being had to the accompanying drawings, forming a part thereof:

In the drawings:

Figures 2, 3 and 4 are, respectively, side, front and rear elevational views thereof.

I claim:

The ornamental design for a book end, substantially as shown.

JULIUS H. WITZKE.
